UNITED STATES PATENT OFFICE.

HENRY W. GRIFFIN, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,211,142.

Specification of Letters Patent. Patented Jan. 2, 1917.

Continuation in part of application Serial No. 744,367, filed January 27, 1913. This application filed June 30, 1913, Serial No. 776,482. Renewed October 13, 1916. Serial No. 125,502.

To all whom it may concern:

Be it known that I, HENRY W. GRIFFIN, a citizen of the United States, residing at New York, in the county of New York, and State 5 of New York, have invented certain new and useful Improvements in Railway Signaling, of which the following is a specification.

My invention relates to railway signaling, and particularly to signaling for stretches 10 of single track over which traffic moves in both directions, such for example as stretches of single track between passing sidings.

I will describe two forms of railway signaling embodying my invention and will 15 then point out the novel features thereof in claims.

The present application is a continuation 20 of my application filed January 27, 1913, Serial No. 744,367, for railway signaling.

In the accompanying drawings, Figure 1 is a diagrammatic view showing a stretch 25 of single track having applied thereto one arrangement of apparatus and circuits embodying my invention. Figs. 2, 3 and 4 are views similar to Fig. 1 but showing the operation of the apparatus during the passage 30 of a car or train through the stretch.

Similar reference characters refer to similar parts in each of the several views.

Referring to the drawings, the reference character A designates the track rails of a stretch of railway track over which traffic moves in both directions. The track rails of the stretch A are electrically separated 35 from the adjoining track rails by insulations 29. The stretch A is provided with a track circuit comprising the track rails, a source of current connected with the track 40 rails adjacent the middle of the stretch and two track relays R and R', connected with the track rails adjacent the ends of the stretch respectively. As here shown, the 45 source of current for the track circuit is a secondary winding 1 of the transformer T, whose primary 2 is supplied with alternating signaling current from a suitable source, not shown in the drawings. Since the signaling current is alternating in character, the track relays R and R' are preferably of a type responsive only to alternating current; as here shown, they are of the vane type. When a track circuit is arranged as

just described, that is, with the source of 55 signaling current adjacent the middle, and a relay adjacent each end, it is well understood that when a car or train enters the stretch from either end, it immediately opens the relay adjacent the entering end, 60 but the relay adjacent the other end is not opened until the car or train reaches a point near the point of connection of the source of current with the track rails, as indicated on the drawings. After the car or train has 65 passed a short distance beyond the point of connection of the source of current with the rails, the relay first opened again closes, but the other relay remains open until the car or train leaves the stretch. The point at 70 which the relay first opened closes is substantially the same as the point at which a car or train moving in the opposite direction causes this relay to open.

Traffic into the stretch A is governed by 75 two end signals S and S', located respectively adjacent the ends of the stretch. Traffic through the stretch is also governed by two intermediate signals B and B'; signal B is located in advance of signal S, but 80 opposite to or in the rear of the point at which an eastbound car or train causes relay R' to open, and signal B' is located in advance of signal S', but opposite to or in the rear of the point at which a westbound car 85 or train causes track relay R to open. Each of the four signals is adapted to indicate "stop" and "proceed"; as here shown, all four of the signals are of the semaphore type, but it is understood that other types 90 of signals may equally well be employed.

The signals are provided with circuits which are controlled by relays R and R', and which are supplied with alternating current by a secondary 7 of transformer T 95 and also by the secondaries of transformers T' and T'', the primaries of these latter transformers being also energized from the source of alternating signaling current. For convenience, I have indicated by plus and minus signs the instantaneous polarities of the secondary 7 and of the secondaries of transformers T' and T''. The circuit for signal B is from the positive side of the secondary of transformer T'', through wire 3, 100 contact 4 of relay R', wire 5, signal B, wire 6, common wire 0, to the negative side of the secondary of transformer T''. Similarly

the circuit for signal B' is from the positive side of transformer T', through wire 8, contact 9 of relay R, wire 10, signal B', wire 11, common wire 0 to negative side of transformer T'. Operatively connected with signal B are three contacts, 12, 13 and 14, and operatively connected with signal B' are three contacts 12^a, 13^a, and 14^a. As here shown, the circuit for signal S is controlled by contact 12 operated by signals B, the circuit for signal S being from the positive side of secondary 7 through wires 15, 16 and 17, contact 12, wires 18 and 19, contact 20 of relay R, wire 21, signal S, common wire 0 to negative side of secondary 7. Signal S' is similarly controlled by contact 12^a of signal B', the circuit for signal S' being from the positive side of secondary 7 through wires 15, 22, 23 and 24, contact 12^a, wires 25 and 26, contact 27, wire 28, signal S', common wire 0 to negative side of secondary 7.

To describe the control of the signals more briefly; signal B is controlled only by relay R'; and signal S is controlled by signal B and also by relay R, hence signal S is in effect controlled by relays R and R'. Similarly, signal B' is controlled only by relay R, and signal S' is controlled by signal B' and by relay R', so that signal S' is in effect controlled by relays R and R'.

It is evident that with the circuits thus far described, when an eastbound car or train passes through the stretch, signal S would indicate stop until the car or train leaves the stretch, this signal being held at stop first by relay R and later by contact 12, which in turn is held open because signal B is held at stop by track relay R'. For similar reasons signal S' would be held at stop throughout the passage of a westbound car or train through the entire stretch. It sometimes is desirable, however, that after a car or train has passed some distance into the stretch A, a following car or train should be permitted to enter the stretch. For this reason I provide means for permitting the end signal S or S' in the rear of a car or train to change to proceed indication after such car or train has passed some distance into the stretch. I will now explain the means here shown by which this control of the end signals is accomplished.

The circuit for end signal S is provided with a shunt around contact 12 and this shunt is opened and closed by an auxiliary relay X. This shunt is from wire 16, through wire 30, contact 31 of relay X, wire 32 to wire 19. Similarly, the control circuit for signal S' is provided with a shunt around the contact 12^a, and this shunt is opened and closed by an auxiliary relay X'. The shunt for this latter circuit is from wire 22, through wire 33, contact 34 of relay X', wire 35 to wire 26. Each of these auxiliary

relays is provided with a pick-up circuit and a holding circuit, which circuits are controlled by the contacts operated by the signals B and B'. The pick-up circuit for auxiliary relay X' is from the positive side of secondary 7, through wires 15, 16 and 17, contact 14, wire 36, back contact 37 of relay X, wire 38, contact 13^a, wire 39, relay X', wires 40 and 11, common wire 0 to secondary 7. This circuit is indicated by heavy lines in Fig. 2. It will be seen that this circuit can be closed only when signal B indicates stop and signal B' indicates proceed and when auxiliary relay X is open. The holding circuit for auxiliary relay X' is from positive side of transformer 7, through wires 15, 22, 23 and 41, contact 42 of relay X', wire 43, contact 13^a, wire 39, relay X', wires 40 and 11 and common wire 0 of secondary 7. This circuit is indicated by heavy lines in Fig. 3. It will be seen that this holding circuit can be closed only when relay X' is closed and signal B' indicates stop. The pick-up and holding circuits for relay X are similar to those just traced for relay X', hence they need not be traced herein.

The operation of the apparatus is as follows: Referring particularly to Fig. 2, when a westbound car or train W enters the stretch A, it first opens track relay R', thereby causing signals S' and B to change to stop indication and the operation of signal B opens the circuit of signal S, which therefore also changes to stop indication. The operation of signal B closes contact 14 thereby closing the pick-up circuit of auxiliary relay X' so that this relay then becomes energized. This pick-up circuit is indicated in Fig. 2 by heavier lines than the other circuits. Referring now to Fig. 3, when the car or train W reaches a point near the middle of the stretch it causes track relay R to open and this relay opens the circuit of intermediate signal B' which latter then changes to stop indication. This operation of signal B' closes contact 13^a and since auxiliary relay X' is already closed, the holding circuit for this relay now becomes closed. This holding circuit is indicated in Fig. 3 by heavier lines than the other circuits. Auxiliary relay X' being closed, the shunt for the control circuit of signal S' is now closed, but this control circuit is still open at track relay R', consequently, signal S' continues to indicate stop.

Referring now to Fig. 4, when the car or train W reaches a point beyond the middle of the stretch it allows track relay R' to close and the control circuit for signal S' is then closed through the shunt controlled by auxiliary relay X'. The control circuit for signal S' is now as indicated in the heavier lines in Fig. 4, and is as follows: from the positive side of secondary 7 through wires 15, 22 and 33, contact 34 of relay X', wire 35 to wire 26. Each of these auxiliary

relay X', wires 35 and 26, contact 27 of relay R', wire 28, signal S', common wire 0 to negative side of secondary 7. Signal S' therefore now indicates proceed, so that a following westbound car or train may enter the stretch A. If the car or train W leaves the stretch A before the following car or train reaches signal B' this latter signal will have changed to proceed indication so that the following car or train may then proceed through the remainder of the stretch A. If, however, the car or train W has not left the stretch A by the time the following car or train reaches signal B', this latter signal will continue to indicate stop and the following car or train must be brought to a stop and must wait until the car or train W leaves the stretch.

The operation of the apparatus during the passage of an eastbound car or train through the stretch A is similar to that which I have just described for a westbound car or train, hence it need not be explained herein.

25 Each of the auxiliary relays X and X' is preferably of a slow-acting type in order to avoid any tendency to open while the relay is being transferred from its pick-up circuit to its holding circuit by contact 13 or 13^a. However, if contacts 13 and 13^a are so constructed that the movable member engages with one contact point before leaving the other point, then the auxiliary relay is not de-energized during the change, and the slow-acting feature of these relays is not absolutely essential.

If two cars or trains moving in opposite directions should enter the stretch A simultaneously, both would find the end signal indicating proceed, and both cars or trains would therefore be authorized to proceed into the stretch at full speed. As soon as these cars or trains enter the stretch however, signals B and B' would both change to stop indication, hence both cars or trains would be brought to a stop and a collision would be prevented. Signals B and B' should, of course, be located far enough apart to enable both cars or trains to be brought to a full stop before colliding, even if both were proceeding at full speed while passing signals B and B'; in other words, the distance between signals B and B' should be equal to or greater than twice the maximum braking distance of the rolling stock.

One feature of railway signaling embodying my invention is the provision of means for permitting two cars or trains proceeding in the same direction to occupy a stretch of track at the same time, both being protected by absolute signals, only a single track circuit being necessary for the entire stretch.

Although I have herein shown and described only one form of railway signaling embodying my invention, it is understood

that various changes and modifications may be made therein within the scope of the appended claims without departing from the spirit and scope of my invention.

Having thus described my invention, what I claim is:

1. In combination, a stretch of railway track over which traffic moves in both directions, two track relays one connected with the track rails adjacent each end of the stretch, a source of signaling current connected with the track rails at a point between said relays, two end signals located respectively adjacent the ends of the stretch, two intermediate signals located respectively on opposite sides of the point of connection of the source of current with the rails, means for controlling each intermediate signal by the track relay on the opposite side of said source and for controlling each end signal by both track relays, and means for each end signal controlled by the intermediate signals for rendering the first-mentioned means ineffective so far as the control of said end signal by the track relay at the opposite end of the stretch is concerned.

2. In combination, a stretch of railway track, two track relays one connected with the track rails adjacent each end of the stretch, a source of alternating signaling current connected with the track rails at a point between said relays, two end signals located respectively adjacent the ends of the stretch, two intermediate signals located respectively on opposite sides of the point of connection of the source of current with the rails, means for controlling each intermediate signal by the track relay on the opposite side of the said source of current and for controlling each end signal by both track relays, and means for each end signal for rendering the first-mentioned means ineffective so far as the control of said end signal by the track relay at the opposite end of the stretch is concerned.

3. In combination, a stretch of railway track, two track relays connected with the rails of the stretch adjacent the ends thereof, a source of signaling current connected with the rails between said relays, two end signals located respectively adjacent the ends of the stretch, two intermediate signals located respectively on opposite sides of the point of connection of said source with the rails and each intermediate signal being located at the point at which a car or train passing through the stretch from the adjacent end opens the track relay at the other end or farther from the source than said point, means for controlling each intermediate signal by the track relay on the opposite side of said source and for controlling each end signal by both track relays, and means for each end signal for rendering the first-mentioned means ineffective so far as

the control of said end signal by the track relay at the opposite end of the stretch is concerned.

4. In combination, a stretch of railway track, two track relays connected with the track rails adjacent the ends of the stretch respectively and arranged to be opened successively by a car or train passing through the stretch, the relay first opened remaining open until after the other relay has opened, means associated with the track rails between said relays for energizing said relays, two end signals located respectively adjacent the ends of the stretch, two intermediate signals located respectively on opposite sides of said energizing means, each intermediate signal being located opposite the point at which a car or train passing through the stretch from the adjacent end opens the track relay at the other end or farther from the energizing means than said point, means for controlling each intermediate signal by the relay on the opposite side of said energizing means and for controlling each end signal by both relays, and means for each end signal for at times removing therefrom the control normally exerted thereon by the track relay at the other end of the stretch.

5. In combination, a stretch of railway track, two track relays connected with the track rails adjacent the ends of the stretch respectively and arranged to be opened successively by a car or train passing through the stretch, the relay first opened remaining open until after the other relay has opened, means associated with the track rails between said relays for energizing said relays, two end signals located respectively adjacent the ends of the stretch, two intermediate signals located respectively on opposite sides of said energizing means, each intermediate signal being opposite the point at which a car or train passing through the stretch from the adjacent end causes the track relay at the opposite end to open or farther from the energizing means than said point, means for controlling each intermediate signal by the track relay at the opposite end of the stretch and for controlling each end signal by both track relays, means comprising an auxiliary relay for each end signal for rendering the first-mentioned controlling means ineffective so far as the control of said end signal by the track relay at the opposite end of the stretch is concerned, and means for controlling said auxiliary relays.

6. In combination, a stretch of railway track, two track relays connected with the track rails adjacent the ends of the stretch respectively and arranged to be opened successively by a car or train passing through the stretch, the relay first opened remaining open until after the other relay has opened, means associated with the track rails be-

tween said relays for energizing said relays, two end signals located respectively adjacent the ends of the stretch, two intermediate signals located respectively on opposite sides of said energizing means, each intermediate signal being located opposite the point at which a car or train passing through the stretch from the adjacent end causes the track relay at the opposite end to open, or farther from the energizing means than said point, a signal circuit for each intermediate signal which circuit is controlled by the track relay at the opposite end of the stretch, a circuit controller operated by each intermediate signal and arranged to be closed or open according as the signal indicates proceed or stop, a signal circuit for each end signal which circuit is controlled by the circuit controller for the adjacent intermediate signal, a shunt for each end signal circuit around the circuit controller for that circuit, an auxiliary relay for closing each shunt, and means controlled by said intermediate signals for closing said auxiliary relays.

7. In combination, a stretch of railway track, two track relays connected with the track rails adjacent the ends of the stretch respectively and arranged to be opened successively by a car or train passing through the stretch, the track relay first opened remaining open until after the other track relay has opened, means associated with the track rails between said relays for energizing said track relays, two end signals located respectively adjacent the ends of the stretch, two intermediate signals located respectively on opposite sides of said energizing means, each intermediate signal being located opposite the point at which a car or train passing through the stretch from the adjacent end causes the track relay at the opposite end to open, or farther from the energizing means than said point, a signal circuit for each intermediate signal which circuit is controlled by the track relay at the opposite end of the stretch, a circuit controller operated by each intermediate signal and arranged to be closed or open according as the signal indicates proceed or stop, a signal circuit for each end signal which circuit is controlled by the circuit controller for the adjacent intermediate signal, a shunt for each end signal circuit around the circuit controller for that circuit, an auxiliary relay for closing each shunt, a second circuit controller operated by each intermediate signal and arranged to be closed or open according as the signal indicates stop or proceed, and a circuit for each auxiliary relay including the last-mentioned circuit controller of the intermediate signal adjacent the other end of the stretch.

8. In combination, a stretch of railway track, two track relays connected with the

track rails adjacent the ends of the stretch respectively and arranged to be opened successively by a car or train passing through the stretch, the track relay first opened remaining open until after the other track relay has opened, means associated with the track rails between said relays for energizing said track relays, two end signals located respectively adjacent the ends of the 5 stretch, two intermediate signals located respectively on opposite sides of said energizing means, each intermediate signal being opposite the point at which a car or train passing through the stretch from the 10 adjacent end causes the track relay at the opposite end to open, or farther from the energizing means than said point, a signal circuit for each intermediate signal which circuit is controlled by the track relay at 15 the opposite end of the stretch, a circuit controller operated by each intermediate signal and arranged to be closed or open according as the signal indicates proceed 20

or stop, a signal circuit for each end signal which circuit is controlled by the circuit 25 controller for the adjacent intermediate signal, a shunt for each end signal circuit around the circuit controller for that circuit, an auxiliary relay for closing each shunt, a pick-up and a holding circuit for 30 each auxiliary relay; and contacts and conductors controlled by the intermediate signals for closing the pick-up circuit of an auxiliary relay when the adjacent intermediate signal indicates proceed and the 35 other intermediate signal indicates stop, and for closing the holding circuit when the auxiliary relay is closed and the adjacent intermediate signal indicates stop.

In testimony whereof I affix my signature 40 in presence of two witnesses.

HENRY W. GRIFFIN.
